UNITED STATES PATENT OFFICE.

EDWARD JONES, OF BOSTON, MASSACHUSETTS.

IMPROVEMENT IN APPARATUS FOR THE MANUFACTURE OF GAS.

Specification forming part of Letters Patent No. 122,025, dated December 19, 1871.

To all whom it may concern:

Be it known that I, EDWARD JONES, of Boston, in the county of Suffolk and State of Massachusetts, have invented certain new and useful Improvements on Stand-Pipes and Mouth-Pieces for Gas Apparatus, of which the following is a specification:

The nature of my invention relates to improvements on stand-pipes and mouth-pieces, for gas apparatus, consisting in the employment of a box or receptacle containing water, surrounding the stand-pipes or mouth-piece leading from the retorts at any suitable place. Said box may be cast on, attached or connected to the stand-pipe or mouth-piece, as may be convenient, and is to be provided with one or more openings, through which the water can evaporate up in the stand-pipe or mouth-piece, and thus dissolve and prevent the accumulations of coal-tar for the purpose of effecting a clear and unobstructed passage for the gas through the stand-pipe and mouth-piece, as will now be fully shown and described.

On the drawing, Figure 1 represents a front elevation of my invention. Fig. 2 represents a central longitudinal section over the line A B taken on Fig. 1; and Fig. 3 represents a cross-section over the line C D, also taken on Fig. 1.

Similar letters refer to similar parts wherever they occur on the drawing.

The object of this my invention is to remove the accumulation of coal-tar in the stand-pipes and mouth-pieces of gas apparatus, for which purpose I surround the stand-pipes or mouth-pieces on one or more sides with a receptacle containing water, and provide the said receptacle with one or more openings, leading in the stand-pipe or mouth-piece, through which the water can evaporate and rise with the gas up through the mouth-piece and stand-pipe, and thus dissolve, soften, and combine with the coal-tar, making it so thin that it will flow easily back to the retorts and thus keep the stand-pipes and mouth-pieces clear from obstructions and allowing the gas from the retorts to be conducted freely to the hydraulic main.

On the drawing, *a* is the gas-retort mouth-piece, and *b* is the lid. *c* is the stand-pipe, the lower end of which rests in a socket attached to the upper side of the mouth-piece *a*, as shown. At a convenient place on the stand-pipe *c* cast on, attach, or connect a receptacle, *d*, that may surround the stand-pipe wholly or in part, as may

be desired. The upper end of the receptacle *d* is provided with one or more openings, *e e e*, on the circumference of the stand-pipe *c*, through which openings the steam from the receptacle *d* will be evaporated and rise upward through the stand-pipe, thus dissolving the coal-tar accumulations in the stand-pipe. The receptacle *d* is provided with a pipe, *f*, stop-cock *g*, and funnel *h*, by which arrangement I can fill the receptacle *d* from the outside. The receptacle *d* may either be attached to the regular stand-pipe, as shown in Fig. 1, or it may be attached to a short piece, *e*, provided in its upper end with a suitable socket or similar arrangement, whereby it may be connected to the ordinary stand-pipe, as shown in Fig. 2. The advantage of the latter arrangement is that old gas-works can easily be provided with my improvement simply by cutting off the ordinary stand-pipes a little and to connect them with the short pipe, *e*, and the receptacle *d* attached thereto, as shown.

The operation of my invention is as follows: When the lid *b* is removed during the charging of the retort, I open the cock *g* and fill the receptacle *d* with water by pouring it through the funnel *h*, and when full I close the cock *g* and replace the lid *b* as usual, when the heat from the retort will gradually evaporate the water contained in the receptacle *d*, that rises up through the stand-pipe, and thus effect the desired object, viz., softening and preventing the coal-tar from accumulating and clogging up the stand-pipe and mouth-piece. Instead of placing the receptacle *d* on the stand-pipe I may also put it around the mouth-piece *a*, as shown in dotted lines *i* on the figures. In this case I can either let my receptacle run all around the mouth-piece, or let it extend only on a part of said mouth-piece, as may be desired.

Having thus described fully the nature, construction, and operation of my invention, I wish to secure by Letters Patent and claim—

A receptacle, *d*, cast onto, attached, or connected to a stand-pipe or mouth-piece for gas apparatus, provided with one or more openings, *e e e*, said receptacle *d* surrounding the stand-pipe or mouth-piece wholly or in part, for the purpose as herein fully set forth and described.

EDWARD JONES.
